BATTERY TERMINAL CONNECTOR

Herbert J. Rich, Glendale, Calif., assignor to
 National Cable & Metal Co., Glendale, Calif.,
 a corporation of California

Application September 14, 1937, Serial No. 163,757

5 Claims. (Cl. 173—259)

This invention relates to and has for an object the provision of a battery terminal connector which is constructed so that it may be readily clamped upon a battery terminal without being distorted to an extent as would impair the operativeness thereof, or a good electrical connection with said terminal.

Another object of this invention is to provide a connector of the character described wherein 10 the clamping lugs which extend outwardly from the body of the connector and are moved together by means of a bolt and nut whereby to clamp the body on a battery terminal, are joined by a web portion which will prevent undesirable 15 distortion of the connector and the terminal, and provide for an easily and quickly effected tight and uniform clamping of said body around said terminal.

I have shown in the accompanying drawing a 20 preferred form of battery terminal connector embodying my invention, subject, however, to modification, within the scope of the appended claims, without departing from the spirit of my invention.

Fig. 1 represents a top plan view of a battery 25 terminal connector constructed in accordance with this invention.

Fig. 2 is a sectional view taken on the plane of line 2—2 of Fig. 1.

Fig. 3 is a sectional view taken on the plane of line 3—3 of Fig. 1.

Fig. 4 is a perspective view showing the connector clamped upon a battery terminal.

Fig. 5 is a top plan view of a modified form 35 of the invention.

Fig. 6 is a sectional view taken on the plane of line 6—6 of Fig. 5.

Fig. 7 is a sectional view taken on the plane of line 7—7 of Fig. 5, and

Fig. 8 is a perspective view of the form of the 40 invention shown in Figs. 5, 6 and 7.

One embodiment of this invention, as shown in detail in Figs. 1 to 4 inclusive, of the accompanying drawing, comprises a radially split 45 apertured body 9 which is in the form of a cylindrical sleeve and is adapted to surround and be clamped upon a battery terminal 10 as indicated in Fig. 4. Opposite its split side this split body 9 is provided with a socket 11 to which a flexible conductor 12 is secured by being clamped therein as is customary in the art.

Extending outwardly from the body on opposite sides of the split are opposed lugs 13—13 50 having bolt receiving apertures 14 extending transversely therethrough. These apertures are

aligned for reception of a bolt 15 on which a nut 16 is mounted in the customary manner. The head of the bolt engages a shoulder 17 on one of the lugs so that upon manipulation of the nut the lugs are moved towards and away from one another as the case may be, whereby to clamp and unclamp the split body 9, it being noted that the lugs 13—13 are spaced apart to provide for this clamping and unclamping action.

To prevent distortion of the lugs and body, 10 upon tightening the nut 16 I provide a connecting web 18 between the lugs 13—13. It will be noted that the connector is usually formed of lead or some other similar soft metal or alloy such that upon tightening the clamping means, 15 distortion of the body and lugs takes place. Unless some means is provided to control this distortion, particularly in the lugs, they will be drawn together so that the outer ends converge and the inner ends spread apart. This distortion tends to likewise distort the battery terminal engaging portions of the clamp so as to impair a good electrical contact. By having the connecting web 18 located between the outer ends of the lugs and the openings 14, said outer 20 ends are prevented from being bent towards one another convergently, as aforesaid, wherein the inner ends of the lugs which are attached to the contractible body are free to move together as desired, whereby to clamp the body uniformly 25 upon the terminal. As here shown this web is comparatively thin and is located at the outer ends of the lugs, being formed during the stamping or molding operation of the connector, and is therefore an integral part thereof. In view of 30 the thinness of the web it is capable of being compressed and will compress under pressure of the clamping means but nevertheless will resist inward movement of the outer ends of the lugs while the inner ends thereof are free to move 35 inward as desired. In other words the lugs 13—13 fulcrum at the web 18.

If desired the lugs may be provided with inward extending projections 19 which would contact one another should the web 18 become ruptured or collapsed, so as to prevent the undesirable distortion of the lugs.

I may construct the connector as shown in Figs. 5 to 8 inclusive, wherein the split body 20 corresponds to the body 9 and the lugs 21 and 22 50 correspond to the lugs 13—13, except that they do not have the inward projections 19. The web 23 is formed integral with the opposite faces of the lugs 21 and 22 at the outer ends of the lugs, and serves the same purpose as the web 18. In 55

this form a bolt 24 and a nut 25 are provided as in the other form, and a flexible conductor 26 is clamped to the connector by means of a socket member 27 on the latter.

It should be noted that the desired leverage action for effecting a uniform clamping of the connector on the battery terminal may be enhanced by locating the bolt as close as possible to the inner ends of the lugs, whereby the lugs 10 have their longer portions between their outer ends and the bolt openings.

It is now seen that with the connector of this invention, when the nut of the clamping means is tightened, the web resists the convergent movement of the outer ends of the lugs, while the inner ends of said lugs are free to move towards one another whereby to clamp the split body uniformly upon the battery terminal. With this arrangement the connector may be clamped and unclamped many times without becoming distorted, to the extent that its operation and an effective electrical contact will be impaired.

I claim:

1. A battery terminal connector comprising an apertured split body formed of soft deformable metal and adapted to be clamped around a battery terminal, opposed spaced lugs of substantially uniform length extended outwardly from said body on opposite sides of the split thereof and being formed integral with said body and having a cross sectional area equal at least to that of the body and having bolt receiving openings therein, a bolt extended through said openings, a nut associated with said bolt for effecting a clamping of said connector and a relatively thin deformable web portion formed integral with and joining said lugs at a point between the outer ends of the latter and said bolt openings and adapted to be distorted to permit of the movement of the lugs towards one another when the connector is tightened.

2. A battery terminal connector comprising an apertured split body of soft deformable metal adapted to be clamped around a battery terminal, opposed spaced and substantially parallel lugs extended outwardly from said body on opposite sides of the split thereof and having bolt receiving openings therein, said lugs being of substantially uniform length and substantially equal in thickness to that of the body, a bolt extended through said openings, a nut associated with said bolts for effecting a clamping of said connector, opposed

aligned and normally spaced abutments extending towards one another from opposite faces of said lugs at the outer ends of said lugs, and a relatively thin deformable web extending between and joining said abutments.

3. A battery terminal connector comprising an apertured split body adapted to be clamped around a battery terminal, opposed spaced lugs extending in substantial parallelism outwardly from said body on opposite sides of the split thereof and adapted to be drawn towards one another to clamp said body around a battery terminal, said lugs having transverse openings between their ends for reception of a clamping bolt, and a comparatively thin, deformable web portion joined to and extending between said lugs at a point between said bolt receiving openings and the outer ends of said lugs, to act as a compressible fulcrum to cause the inner ends of said lugs to come closer together than said outer ends when said lugs are drawn towards one another.

4. A battery terminal connector comprising an apertured split body adapted to be clamped around a battery terminal, lugs extending outwardly from said body on opposite sides of the split thereof and in substantial parallelism, being spaced apart substantially throughout their length, means operative between the ends of said lugs for moving them together to clamp said body on said terminal and a relatively thin flat and narrow compressible web portion joining said lugs adjacent their outer ends and disposed between the upper and lower faces of said lugs.

5. A battery terminal connector comprising an apertured split body adapted to be clamped around a battery terminal, opposed parallel lugs extended outwardly from said body on opposite sides of the split thereof and having aligned bolt receiving openings therein, a bolt extended through said openings, a nut associated with said bolts for effecting a clamping of said connector and a relatively thin compressible web portion formed integral with and joining said lugs at a point between the outer ends of the latter and said bolt openings and between the upper and lower faces of said lugs, said lugs being of greater width between their outer ends and said bolt openings than between their inner ends and said bolt openings, and being normally spaced apart by said web portion.

HERBERT J. RICH.
